US0D1028113S

(12) United States Design Patent (10) Patent No.: US D1,028,113 S
(45) Date of Patent: * May 21, 2024

(54) DISPLAY SCREEN WITH ICON

(71) Applicant: NIKE, Inc., Beaverton, OR (US)
(72) Inventor: Chris Le Howard, Salt Lake City, UT (US)
(73) Assignee: NIKE, Inc., Beaverton, OR (US)
() Term: 15 Years
(21) Appl. No.: 29/816,793
(22) Filed: Nov. 24, 2021
(51) LOC (14) Cl. 14-04
(52) U.S. Cl. USPC D14/495

(58) Field of Classification Search

USPC ..... D14/485-495; D21/576, 585, 593, 594, D21/621, 623, 627, 630, 649, 659; D11/136, 149, 150, 158, 160; D20/31 CPC . CLAIM

The ornamental design for a display screen with icon, as shown and described.

DESCRIPTION

The FIGURE is a front view of a display screen with icon showing my new design.

The broken line shows a display screen and forms no part of the claimed design. The white space between the icon and the broken line forms no part of the claimed design.

1 Claim, 1 Drawing Sheet
